(57) CLAIM

The ornamental design for a support for a table top, as shown and described.

DESCRIPTION

FIG. 1 is a perspective view of a support for a table top; FIG. 2 is a top view of the support for a table top shown in FIG. 1;

FIG. 3 is a right side view of the support for a table top shown in FIG. 1;

FIG. 4 is a left side view of the support for a table top shown in FIG. 1;

FIG. 5 is a right side view of the support for the table top shown in FIG. 1, with the left side being a mirror image thereof; and,

FIG. 6 is a bottom view of the support for a table top shown in FIG. 1.

The broken lines are for illustrative purposes only and form no part of the claimed design.
